TELEGRAPH EXCHANGE SYSTEM

Gilbert S. Vernam, Hackensack, N. J., assignor to International Communications Laboratories, Inc., New York, N. Y., a corporation of New York

Application May 21, 1931. Serial No. 538,981

8 Claims. (Cl. 178—4.1)

My invention relates to improvements in telegraph exchange systems and particularly to the manner in which motors and printers are controlled in the operation of such systems.

5 In telegraph systems wherein the customers are provided with printing telegraph apparatus, it is essential or desirable to control the starting and stopping of the motors associated with such apparatus. The control of the motors is 10 exercised at a concentration board where the various customers' lines terminate.

A customer desiring to send a message signals the concentration board, whereupon an operator responds to the signal by placing a cord circuit in association with a jack in which the customer's line terminates, whereupon the motor at the customer's station is placed in operation. The customer then operates his printer 20 and sends the message which is recorded upon a printer connected with the cord circuit associated with his line.

The printer associated with the concentration board is also arranged to transmit a message to the printer at the customer's station.

25 The operation of the motor is controlled over the customer's line which is provided with a relay and rectifier in such a manner that, when current of one polarity is connected to the line, the relay is energized, and when the current is reversed the relay is de-energized and the motor started to allow the customer to send his message.

30 After the message has been sent, the operator at the concentration board removes the cord circuit from association with the customer's line, which causes the control relay associated with the rectifier to become energized and stop the motor.

35 Other features of my invention will be described in the description to follow.

40 My invention is illustrated in the accompanying drawing wherein:

45 Fig. 1 shows a customer's station provided with a printer and control apparatus together with the concentration board;

Fig. 2 shows a modification of the cord circuit of Fig. 1;

50 Fig. 3 shows the construction of the rectifier and control relay.

55 Referring to Fig. 1, the customer's station is provided with a signal key 1, printer keyboard contacts 2, printer magnet 3, motor 8, rectifier 4 and control relay 5 bridged across the rectifier.

The customer's station line is extended to a

signal relay 100 through contacts of a jack 101 at the concentration board.

The cord circuit terminating in the plug 102 is provided with a line relay 103, a sleeve relay 24 and release relay 35. Associated with the 60 cord circuit is a printer magnet 36, motor 37 and keyboard contacts 39.

The cord circuit of Fig. 2 is provided with similar equipment and is equipped with a battery reversing switch 48. The difference in operation of this circuit will be described later.

65 Referring to Fig. 3, the rectifier comprises a number of copper discs 13, coated on one side with copper-oxide and separated by lead washers, bolted together by means of the nuts 50—51 70 and the bolt 52 and mounted upon a bracket 60. This bracket is fastened to a support 61 by means of the bolts 62.

75 The core of control relay coil 5 is fastened to the extension 72 of the bracket 60 by the rivet 73 or screw 73. The armature 70 is pivoted to the bracket at 71. The extension 69 of the armature engages the projection 68 on the base 65 which is pivoted to the extension 63 of the bracket at 64. The base 65 is provided with 80 two clamps 66 and 67 which grip the glass case 76 which contains mercury for closing contacts 6 when that end of the case 76 is tilted downward.

85 A tension spring 75 extends from the lower part of armature 70 to the arm 78 to hold the armature and the glass container in the position shown.

When the armature 70 is attracted toward the core 74 the extension 69 forces the right end 90 of base 65 downward and tilts the container 76 so that the mercury opens contacts 6.

95 The operation of the system shown in Fig. 1 is as follows:

The customer or subscriber desiring to send a message operates the signalling key 1 momentarily which removes ground from his line extending to the concentration board, thus opening the circuit extending in series through the winding of relay 5 and winding 14 of the 100 signal relay 100.

105 The signal relay becoming de-energized closes contacts 17 and completes the circuit of the signal lamp 19 through the jack contacts 18. The closing of contacts 15 short-circuits the winding 14 to prevent the relay from again operating when the key 1 is again closed after its momentary operation.

110 The operator at the concentration board, observing the lighting of lamp 19, places the plug

102 of the cord circuit into the jack 101 causing the separation of contacts 18 and 20. The separation of contacts 18 opens the circuit of the lamp 19, while 20 disconnects winding 14 of the signal relay 100 from the line extending to the customer's station. The signal relay is now held energized by the following path: battery 80, winding 16, sleeve 12 of the jack 101, sleeve 23 of the plug 102, winding of relay 24 to ground.

10 Relay 24 operating, closes the circuits of the supervisory signal 29 in series with the guard lamp 30, as follows: battery 90, switch 38 (which is normally closed), contacts 25, lamps 29 and 30, contacts 31 and 32 of relay 35 to ground.

Positive battery 90 is connected to the winding 41 of line relay 103, as follows: battery 90, switch 38, contacts 25, resistance 42 and winding 41 to ground. Positive battery 90 is also connected to the printer magnet 3 at the customer's station as follows: 90, keyboard contacts 39, 40, 22, 21, 11, rectifier 4, 3, 2 to ground. Rectifier 4 is so connected that this positive battery supply permits current to pass through it. As rectifier 4 is in shunt with winding of relay 5, it in effect short-circuits this relay winding, causing the relay to release and close its contacts 6 which complete the circuit of motor 8.

20 Positive battery 90 flowing through winding 40 of polar relay 103 is greater, in effect, than that flowing through winding 41. Energization of winding 41 tends to open relay contacts 46 while energization of winding 40 will cause contacts 46 to close. Battery 90, therefore, will extend to printer magnet 36, as follows: 90, 38, 25, 43, 46, 28, 27, 36 to ground.

25 The customer now operating his printer keyboard contacts 2 causes the operation of printer magnet 3 and the line relay 103. The operation of this line relay opens and closes the circuit of the printer magnet 36. The telegraph operator at the concentration office may also operate the printer keyboard contacts 39, which will likewise cause the operation of the line relay 103, the printer magnet 36 and printer magnet 3 at the customer's station.

30 The telegraph operator at the concentration office in order to terminate a call depresses key 34, which operates locking relay 35. The operation of this relay opens the circuit of lamps 29 and 30.

35 The operator at the concentration board noting the extinguishing of lamps 29 withdraws the plug from the jack which causes contacts 20 to close and connect negative battery 80 through winding 14 of the signal relay to the station circuit.

40 As the current from negative battery 80 will not flow through the rectifier 4, it will instead flow through winding of relay 5 which in operating stops the motor 8.

45 The withdrawal of the plug from the jack also causes relays 24, 35 and 103, to become de-energized, restoring all circuits to normal.

50 It should be noted that, with this circuit, if the concentration board operator should, by mistake, plug up a calling line to an unoccupied printer position where the power switch 38 is turned off, no line current will be supplied to the station line, thus leaving the customer's printer inoperative. The fact that the supervisory lamp 29 at the concentration board does not light indicates to the concentration board

operator that the line has been connected to a printer having the power switch turned off.

55 The circuit shown in Fig. 2 is arranged to give positive supervision, that is, the supervisory lamp 29 at the concentration board is extinguished when the associated printer set is either idle or normally working, and the lamp lights only to indicate that some action is required on the part of the concentration board operator. In this circuit, both negative and positive battery are supplied to the central office printer positioned by the switch 48. When the position is occupied by an operator, the switch 48 is normally turned to the right. This connects positive battery to the printer 90 motor 37 and through contacts 26 and 27 of the sleeve relay 24 to the printer magnet 36. If the plug is inserted into the jacket of a station line, the sleeve relay 24 will operate and connect positive battery to the line, starting the 95 station motor. As before, the sleeve relay 24 connects the printer magnet 36 to the contacts of the line relay. It also lights the guard lamp 30 at the printer set, but the supervisory lamp 29 at the concentration board does not 100 light, as its circuit is open at the contact 53 of relay 35 and also at the power switch 48.

105 As before, the printer operator may signal to disconnect, by momentarily operating the release key 34. This operates a lamp relay 35 which locks itself, extinguishes the guard lamp 30, and lights the supervisory lamp 29. When the plug is withdrawn from the jack at the concentration board, the sleeve relay 24 releases, extinguishing the supervisory lamp 29, releasing the lamp relay, and restoring the circuit to its normal position. It should be noted that if the customer should operate his keyboard contacts 2 before the concentration board operator has withdrawn the plug, the line relay 103 will release momentarily, releasing the lamp relay 35 and thereby extinguishing the supervisory lamp 29 and lighting the guard lamp 30.

110 If the switch 48 had been turned to the left or "off" position at the time the plug was inserted into the station line jack, negative battery would have been connected to the station line, with the result that the customer's printer motor 8 would not start. Under these conditions, the supervisory lamp 29 would light, as well as the 125 guard lamp 30. If the printer operator now switches on the power, this will extinguish the supervisory lamp 29, start her printer motor 37, and at the same time, reverse the line current 130 to start the customer's printer motor 8.

135 What is claimed is:

1. In a control system, a printer associated with a line circuit, a printer motor having a power circuit, a relay, a mercury switch adapted to close said power circuit upon the release of said relay and to open it upon the operation of said relay, and a rectifier included in said line circuit and bridged by said relay, for causing the operation of said relay when current of one polarity is connected to said line circuit and the release of said relay when current of the opposite polarity is connected thereto.

140 2. In a printing telegraph exchange system, a subscriber's station connected by a line to a central station at the subscriber's station, a printer motor having a power circuit, a mercury switch adapted to close said power circuit upon the release of said relay and to open it upon the operation of said relay, and a rectifier included in said line and bridged by said relay for caus-

- ing the operation of said relay when the direction of current in said line is normal and the release of said relay when the normal direction of current in said line is reversed.
5. In a printing telegraph exchange system, a central station, a subscriber's station connected thereto by a closed line terminating in a switchboard at the central station, a printer at said subscriber's station, a printer motor adapted to be started in response to a reversal of the normal direction of current in said line, a cord circuit for connecting a central station printer through said switchboard to said line, means in said cord circuit responsive to said connection for normally reversing the direction of current in said line and for lighting one lamp associated with said switchboard and another associated with said central station printer, and manually operable switching means in said cord circuit for preventing both the reversal of current in said line and the lighting of said lamps upon the operation of said last-mentioned means.
4. In a printing telegraph exchange system, a subscriber's station connected to a central station by a closed line terminating in a switchboard at the central station, said subscriber's station having a printer and a printer motor adapted to be started in response to a reversal of the normal direction of current in said line, a cord circuit for connecting a central station printer through said switchboard to said line, means in said cord circuit responsive to said connection for reversing the current in said line and for lighting a lamp associated with the central station printer, and manually operable switching means in the cord circuit for preventing the reversal of current in said line and for effecting the lighting of the lamp associated with the central station printer and another lamp associated with the switchboard upon the operation of the last-mentioned means.
5. In a printing telegraph exchange system, a central station, a subscriber's station connected thereto by a closed line terminating in a switchboard at the central station, a printer at the subscriber's station, a printer motor adapted to be started in response to a reversal of the normal direction of current in said line, a central station printer remote from said board and connectable to said line by a cord circuit cooperating with said switchboard, means responsive to said connection for normally reversing the direction of current in said line, manually operable switching means for preventing said current reversal in response to said connection, and indicating means at said switchboard for indicating when the current in said line is reversed by the connection of said printer to said line and when this current reversal fails to take place.
6. In a control system, the combination of a printer associated with a line circuit, a printer motor having a power circuit, a mercury switch for controlling said power circuit, a relay for controlling said mercury switch, and a rectifier connected in said line circuit and bridged by said relay for controlling the latter in accordance with the direction of current flow in said line circuit.
7. In a printing telegraph exchange system, the combination of a subscriber's station connected to a central station by a line circuit normally in one condition, means under control of the central station for changing the condition of said line circuit, a printer at the subscriber's station, a printer motor having a power circuit, a mercury switch for controlling said power circuit, a relay for controlling said mercury switch, and a rectifier connected in said line circuit and bridged by said relay for controlling the latter in accordance with the condition of said line circuit.
8. In a printing telegraph exchange system, the combination of a subscriber's station connected to a central station by a line circuit normally in one condition, means for changing the condition of said line circuit, a printer at the subscriber's station, a printer motor having a power circuit, a mercury switch for controlling said power circuit, a relay for controlling said mercury switch, and a rectifier connected in said line circuit and bridged by said relay for controlling the latter in accordance with the condition of said line circuit.
